UNITED STATES PATENT OFFICE.

MARTHA HALOWELL CONNOR, OF BALTIMORE, MARYLAND, ASSIGNOR TO THE TIN DECORATING COMPANY OF BALTIMORE, OF BALTIMORE, MARYLAND, A CORPORATION OF NEW JERSEY.

DESIGN FOR A BOX COVER OR SIMILAR ARTICLE OF MANUFACTURE.

Application filed November 14, 1921. Serial No. 515,141. Term of patent 7 years.

To all whom it may concern:

Be it known that I, MARTHA HALOWELL CONNOR, a citizen of the United States, residing in the city of Baltimore, State of Maryland, have invented a new, original, and ornamental Design for a Box Cover or Similar Article of Manufacture, of which the following is a specification, reference being had to the accompanying drawing, forming a part thereof, wherein the figure is a perspective view of a box structure having my ornamental design applied to the cover thereof.

The design is shown as embodied in or applied to a box cover but I contemplate that the same may be also embodied in or applied to other analogous articles of manufacture.

What I claim is:

The ornamental design for a box cover or similar article of manufacture substantially as shown and described.

MARTHA HALOWELL CONNOR.
